TRUCK BOLSTER DAMPING MEANS

Emil H. Piron, New York, N. Y., assignor to Transit Research Corporation, New York, N. Y., a corporation of New York

Application January 30, 1950, Serial No. 141,211

3 Claims. (Cl. 105—193)

This invention relates to rail car trucks and the like, wherein it is important to damp the swinging or oscillating movements of a body such as a truck bolster. The principal object is to provide a new and improved motion damping means which will frictionally resist such swinging in proportion to the violence of the shock which produces the swinging motion.

Rail trucks generally comprise a truck frame and a swing bolster supported by the frame either on springs located at each end thereof or by swing links which may support the bolster directly, or which may support a spring plank which carries springs which in turn support the bolster. In any case, a lateral displacement of the truck sets up a lateral motion of the car body which is carried by the bolster. This motion becomes a more or less continuous lateral oscillation unless it is damped. Conventionally the damping is done by shock absorbers or by snubbers.

The main drawbacks to the use of prior art devices revolve around difficulty of regulating those devices to respond in proportion to the violence of the lateral shock and to the difficulty of maintaining the regulation once it has been made. For instance, the resistance of hydraulic shock absorbers can be ascertained only by measurement in a testing machine and is never known with accuracy after short service. In the case of friction blocks the surfaces wear and must be adjusted at more or less frequent intervals.

I have found that it is possible to damp such an oscillating motion by arranging to bias the bolster in its snubbers so that the action of the snubbers can be reinforced by increasing their friction. More particularly it is a principal object of this invention to provide means operative at a substantial distance from the center of a bolster to cause the bolster to partially rotate about its king pin in response to an impact thereagainst by the truck frame thereby causing a biasing action proportionate to the violence of the lateral movement.

The most successful presently used snubber is composed of rubber blocks against which the bolster has rubbing engagement. If the lateral shocks were all of the same intensity such blocks could be adjusted for perfect snubbing. Since the shocks vary greatly in intensity it thus becomes the problem to obtain the effect of adjusting the blocks automatically to set up a friction proportionate to the violence of the shock. I have found that this effect may be obtained by causing the bolster to bias against the snubber blocks.

More specifically it is the object of this invention to provide a bolster support which may swing with subbing friction against friction surfaces, preferably of rubber, and to provide means for causing the bolster to rotate about an axis parallel to the friction surfaces in response to relative movement of the truck frame upon which the bolster is supported.

The invention will be better understood with reference to the accompanying drawings in which its application to one type of truck is illustrated and in which:

Figure 1 is a side elevation of a rail truck equipped with my improved bolster snubbing arrangement,

Figure 2 is a top elevation of the truck of Figure 1,

Figure 3 is a detail view of the bolster of the truck of Figure 1 with its snubbers,

Figure 4 is a side elevation of the bolster of Figure 3,

Figure 5 is a top elevation of a rail truck showing a modification of my invention incorporated therein,

Figure 6 is a side elevation of the truck of Figure 5,

Figure 7 is an enlarged vertical section taken along either line 7—7 of Figure 5, and

Figure 8 is an enlarged vertical section taken along either line 8—8 of Figure 5.

More particularly, 1 indicates the main side frames of a rail truck, which are connected at their ends to the housings 2 of axles 3. These side frames with the axle housings constitute the truck frame. The axle housings include housings 4 for gears (not shown), one of which in each case is carried on the end of the propeller shaft 5 of a main driving motor 6, as shown in Figure 2.

Each motor 6 is carried by a motor supporting cross-beam 7 which is connected at each end to a main frame member 1.

Between the motor supports 7 the truck bolster 8 is supported at each end by large springs 9 which rest upon the side frames 1. These springs 9 yieldingly resist both vertical and lateral swinging movements of the bolster 8 with respect to the side frames 1. Each end of the bolster 8 has flat surfaces 10 (Figure 2) in rubbing contact with blocks of rubber 11. These blocks of rubber are each supported by brackets 12 (see Figures 1 and 2) mounted on the frames 1. These blocks of rubber 11 are transom-like in their action in that they aid the springs 9 to transmit accelerating and retarding forces between the side frames and the bolster, and they are also snubbers since they offer frictional resistance to the swinging movements of the bolster. The blocks 11 may be compressed against the surfaces 10 or merely loosely placed for contact therewith.

The truck as described to this point is further described and claimed in my co-pending application Serial #669,323, filed May 13, 1946, now abandoned.

While the rubber to metal surfaces of the blocks 11 and the surfaces 10 have a very satisfactory life, from a commercial standpoint, there are many times when the play develops by wear because of lack of alert maintenance. More important, damping by friction snubbers can not generally be regulated according to the violence of the shock. The additional construction now to be described causes the damping to increase with an increase in the forces causing swinging movements of the bolster.

Extending outwardly from each side of the bolster near diagonally opposite points are two brackets 13 which carry blocks of rubber 14 so positioned that, with lateral swinging movements of the bolster, they will contact a bracket 12 which is fixed to a side frame 1. Since these contacts are made only after some swinging movement of the bolster has occurred and, then, only at diagonal points the bolster is slightly rotated by the contact thus biasing it in the snubbers 10, 11. The blocks 14 project out of the brackets 13 for a substantial distance allowing for additional swinging movement of the bolster after the contact is made.

The foregoing may be better understood with reference to Figure 3 in which it is seen that after contact of the blocks 14 with the brackets 12 the blocks may be crushed or compressed by an amount d according to the violence of the swinging movement of the bolster 8 thus developing a lateral reaction F which varies with the value of d , so that

$$F=f(d)$$

The force F is developed in a plane at a distance l

from the center A of the bolster, which is its pivotal point, and produces a pivotal action equal to the moment Fl . Now, if b is the distance between the longitudinal center lines through the snubbers 10, 11, the moment Fl produces a pressure

$$\frac{Fl}{b}$$

on one rubber block 11 at each side of the truck. And if c is the coefficient of friction between the surface 10 and the rubber blocks 11, the frictional force developed in the vertical transverse plane is

$$2c \frac{Fl}{b}$$

which opposes the force F . From this it is seen that if

$$2c \frac{Fl}{b} = F$$

or

$$2c \frac{l}{b} = l$$

or

$$2cl = b$$

the frictional force is equal to the lateral force, the damping is as strong as the oscillating force and there is no freedom of oscillation.

In order to preserve softness and some freedom of oscillation it is necessary to make

$$2c \frac{Fl}{b}$$

less than F or

$$2c \frac{l}{b}$$

less than l or $2cl$ less than b .

Although construction limitations generally do not permit the possibility of making $2cl$ approach closely the value of b it is possible to improve the approach and thus to improve greatly the damping effect.

Figures 5 to 8 illustrate a modification of my invention. In this case the truck is composed of side rails 15 connected to the housings 16 for axles 17. The axles 17 are supported by wheels 18. Cross-beams 19 support the driving motors 20. A bolster 21 is supported at each end by three springs 22, 23 and 24 for relative vertical and lateral movements with respect to the side frames 15. Brackets 25 extending outwardly from the side frames 15 support rubber blocks 26 at each side of and towards each end of the bolster 21 for frictional contact with the bolster at the surfaces 27. The blocks 26 and the surfaces 27 constitute the snubbers.

The springs 22 and 23 are coil springs seated top and bottom in flat seats 28 provided in the bolster and in flat seats 29 provided on the side frames 1. They thus resist lateral movements of the bolster with respect to the side frames. Please note that the spring 22 at one end of the bolster is diagonally opposite the spring 22 at the other end of the bolster. The springs 24 are seated top and bottom in rocker plates 30 in the bolster 21 and in rocker plates 31 on the side frames 15. These rocker plates have rockers 32 seated in depressions 33, in each instance, which permit the springs 24 and the seats 30 and 31 to rock in response to lateral swinging movements of the bolster. The springs 24 thus offer substantially less resistance to lateral swinging movements of the bolster than do the springs 22 and 23. The result is that when the bolster 21 swings the supporting springs 70 impart a slight rotation to the bolster thus biasing it in its snubbers. The result is quite similar to that previously described.

Various changes may be made without departing from the spirit of my invention and I therefore desire to be

extended protection as defined by the scope of the appended claims.

I claim:

- 5 1. In a rail truck, the combination of a main frame including transom-like cross-members, a bolster between said members, a set of springs supporting each end of said bolster from said frame, each of said sets comprising a plurality of springs arranged side by side, the springs composing each said set being oppositely offset from the longitudinal center line of said bolster, one spring of each of said sets having less load deflection resistance in the direction of the swinging movements of said bolster than the other spring in its set, friction motion damping means positioned on said cross members in slightly spaced relation with respect to the sides of said bolster, said springs by reason of the differential in resistance offered thereby setting up a couple in a horizontal plane causing partial rotation of said bolster in response to swing movements thereof whereby said bolster biases against said damping means.
- 10 2. In a rail truck, a truck frame having transom-like cross-members, spring sets supporting each end of said bolster from said frame and adapted to yieldingly resist all relative vertical and lateral movements thereof, each 25 of said spring sets being composed of at least two springs having their axes in a plane normal to the median plane vertically bisecting said bolster and seated on opposite sides of said plane, one of the springs of each said set having a lower load deflection characteristic in the direction of the lateral swinging movements of said bolster than the other spring in its set, friction pads on each side of said bolster near both ends of said bolster, said spring sets being reversely arranged with respect to each other, said springs by reason of their differential resistance to swinging movements of the bolster setting up a couple whereby said bolster biases against said friction pads in response to relative lateral movements between said frame and said bolster.
- 30 3. In a rail truck, a truck frame having transom-like cross-members, a swing bolster between said members, spring sets supporting each end of said bolster from said frame and yieldingly adapted to resist all relative vertical and lateral movements thereof, each of said spring sets being composed of at least two springs laterally spaced from each other, one of the springs of each of 45 said sets seating firmly against said frame and said bolster, another of the springs of each said set having a spring cap on at least one end thereof, said spring cap having a rocker exteriorly of its spring in rocking relation with respect to said bolster or said frame, said rocker having its axis normal to the direction of the swinging movement of said bolster whereby said springs offer different resistance to lateral swinging movements of said bolster, friction pads carried by said transom-like members at each side of and at each end of said bolster, the spring set at one end of said bolster being arranged reversely to the spring set at the other end thereof, said springs by reason of their differential resistance to swinging movements of said bolster setting up a couple whereby 50 said bolster may bias against opposite friction pads during relative lateral movements between said truck frame and said bolster.
- 40 4. In a rail truck, a truck frame having transom-like cross-members, a swing bolster between said members, spring sets supporting each end of said bolster from said frame and yieldingly adapted to resist all relative vertical and lateral movements thereof, each of said spring sets being composed of at least two springs laterally spaced from each other, one of the springs of each of 45 said sets seating firmly against said frame and said bolster, another of the springs of each said set having a spring cap on at least one end thereof, said spring cap having a rocker exteriorly of its spring in rocking relation with respect to said bolster or said frame, said rocker having its axis normal to the direction of the swinging movement of said bolster whereby said springs offer different resistance to lateral swinging movements of said bolster, friction pads carried by said transom-like members at each side of and at each end of said bolster, the spring set at one end of said bolster being arranged reversely to the spring set at the other end thereof, said springs by reason of their differential resistance to swinging movements of said bolster setting up a couple whereby 55 said bolster may bias against opposite friction pads during relative lateral movements between said truck frame and said bolster.
- 50 5. In a rail truck, a truck frame having transom-like cross-members, a swing bolster between said members, spring sets supporting each end of said bolster from said frame and yieldingly adapted to resist all relative vertical and lateral movements thereof, each of said spring sets being composed of at least two springs laterally spaced from each other, one of the springs of each of 45 said sets seating firmly against said frame and said bolster, another of the springs of each said set having a spring cap on at least one end thereof, said spring cap having a rocker exteriorly of its spring in rocking relation with respect to said bolster or said frame, said rocker having its axis normal to the direction of the swinging movement of said bolster whereby said springs offer different resistance to lateral swinging movements of said bolster, friction pads carried by said transom-like members at each side of and at each end of said bolster, the spring set at one end of said bolster being arranged reversely to the spring set at the other end thereof, said springs by reason of their differential resistance to swinging movements of said bolster setting up a couple whereby 60 said bolster may bias against opposite friction pads during relative lateral movements between said truck frame and said bolster.
